UNITED STATES PATENT OFFICE.

LOUIS GILLET, OF NEVADA, ASSIGNOR TO ANDREW H. SHREFFLER, OF JOLIET, ILLINOIS.

CORN-SHELLER.

SPECIFICATION forming part of Letters Patent No. 247,338, dated September 20, 1881.

Application filed December 27, 1880. (No model.)

To all whom it may concern:

Be it known that I, LOUIS GILLET, of Nevada, in the county of Livingston and State of Illinois, have invented certain new and useful 5 Improvements in Corn-Shellers, of which the following is a specification.

My invention relates to improvements in power corn-shellers, the object of the same being to increase the capacity, durability, cheapness, and efficiency of such machines.

In the accompanying drawings, which form part of this specification, Figure 1 is a side elevation of a corn-sheller embodying my invention. Fig. 2 is a vertical longitudinal section 15 of the same, taken through the center of one of the feeding-holes. Fig. 3 is a cross-section on line 3 of Fig. 2. Figs. 4, 5, 6, 7, 8, and 9 are detail views, showing parts hereinafter to be described.

20 The same letters of reference indicate the same or corresponding parts wherever used.

In said drawings, A represents the frame of the machine mounted upon the carriage A'. B is the feed-elevator, which delivers the corn 25 to the machine. B' is the cob-elevator, and B² is the elevator by which the shelled corn is delivered from the machine. The stripper or shelling wheels C, bevel runners C', picker-wheels C², force-feed C³, fan or blower C⁴, and 30 screw-conveyer C⁵ are all connected with suitable gearings or driving mechanisms, and may be of any ordinary construction.

The separator, or mechanism for separating the corn from the cobs and husks, consists of 35 a screen or series of loose rods, d, hinged at their lower ends to the transverse rod d', and resting freely upon the comb-shaped cob-carriers d², between the teeth thereof, the teeth serving at the same time to keep the rods parallel to 40 and equidistant from each other. The upper ends of the rods d are curved downward, as shown at d³, so that when the combs pass over the sprocket-wheels d⁴ the teeth will project the cobs well onto the second separator or cob-carrier, D, by which the cobs are conveyed to the cob-elevator B'. The combs d² are riveted or otherwise secured at each end to corresponding 45 links of the two endless chains d⁵, one on each side of the separator, the chains being carried 50 upon and driven by the sprocket-wheels d⁶.

The upper ends of the rods d are entirely free, being simply supported by the combs as they are carried along on the endless chains d⁵, the teeth of the combs serving to keep the rods apart and in place, and to clean out and keep open the space between the rods, so that the shelled corn will readily drop through the screen, as well as to carry away the cobs and husks. By this arrangement, as the screen is always kept perfectly clean by means of the combs, and as the rods are also loose and slightly movable under action of the moving combs, the corn is very thoroughly separated from the cobs and husks without the necessity of giving to the screen any shaking or vibratory motion, as has heretofore been usually done. By thus dispensing with this vibratory or shaking motion I am on that account enabled to run the whole machine at a much greater speed, thus not only increasing the capacity of the machine, but also its 60 efficiency. I also thus avoid the wear and tear of the machine due to the vibration of the entire structure caused by the shaking motion of the separator. The rods d, I prefer to make round, as that shape is better adapted to allow 65 the corn to fall through the screen. The corn, after it falls through the screen, drops down upon the inclines E E', and then into the screw-conveyer C⁵, whence it passes to the corn-elevator B², which is provided with a movable 70 spout, B³, for delivering the corn.

The oblique ratchets G, which serve to regulate the passage of the corn-ears into the machine, and at the same time to give to the ears a rotary motion, so that the shelling-wheels 85 will act on all sides or parts of the ear, are secured rigidly to the straps or bars g by means of rivets g', which are pivoted at their other ends to the cast spring-holders g², so as to allow a slight vibratory movement to the ratchets G, for the purpose of causing the same, by means of the spring g³, to press against the corn-ears, whatever may be their size. The end of the strap g fits in a recessed seat in the spring-holder, and g⁴ is the lug or pin which 90 holds it in place. This lug or pin is cast with the spring-holder, as that is the cheaper construction. It fits loosely in a hole near the end of the strap g, so as to allow the vibratory movement of the same before described. 95 100

One end of the spring g^3 is secured in a mortise in the end of the spring-holder, and its other end is held in place by a staple, g^5 , on the end of the ratchet.

5 g^6 is the bolt which holds the spring. It is provided with a thumb-nut, g^7 , for regulating the tension of the spring.

Heretofore the strap to which the ratchet is riveted has been riveted fast at its other end 10 to the spring-holder, and great difficulty has been experienced from the strap breaking, due to its constant vibration and the strains put upon it. Besides avoiding this difficulty, by employing a pivoted ratchet, as described, I am 15 enabled to use a much lighter and cheaper spring, and also at the same time to press the ratchet against the varying-sized ears of corn with much greater promptness and efficiency.

Fig. 7 is a cross-section on line 7 of Fig. 5. 20 Fig. 4 is a detail view, in perspective, looking up against the ratchets.

H H are castings forming the part of the hopper above the bevel runners, just back of the ratchets, or rather between the bevel runners 25 at their larger diameters, and provided with side projections, h , for the purpose of deflecting the corn-ears toward the shelling-wheels between the bevel runners at their smaller diameters, and thus preventing any corn-ears 30 from being carried through the machine unshelled or imperfectly shelled. But for these projections h , if a corn-ear chances to strike the bevel runner near its larger diameter, there is a tendency, on account of the greater velocity 35 of this part of the bevel runner, to lift the ear or carry it directly through the machine without coming in contact with the stripper or shelling-wheels, and especially is this the case when another ear is passing through at the same time.

40 Much of the imperfect work of corn-shellers is due to this difficulty, which I have thus obviated.

Certain parts of the machine shown in the

drawings of this my specification are the invention, as I believe, of Milo L. Cook; and I 45 hereby disclaim the improvements claimed by him in his application of even date herewith, the parts so disclaimed being the device for elevating the corn-ears, consisting of a series of elevating-chains with links having projections, 50 an elevating-trough provided with trucks for the elevating-chains, and the device for adjusting said chains independently of each other; the device for properly guiding the corn-ears into the feed-holes, consisting of the upper and lower 55 guards attached to the end of the elevator; the vibratory back having a flexible flap at its lower edge operated by my movable combs, and the screen of fixed rods in connection with a series of movable combs having short teeth on their 60 lower edge.

What I claim is—

1. In a corn-sheller, the combination of a screen of loose rods with movable comb-shaped cob-carriers, which support said rods between 65 their teeth, substantially as specified.

2. The combination of the combs, endless chains, sprocket-wheels, and screen composed of loose rods, substantially as specified.

3. The combination of the movable combs 70 with the loose rods hinged at their lower ends, whereby the rods are given a slight quiver or motion for the purpose of better separating the corn from the cobs and husks, substantially as specified.

4. The combination, with the bevel runners and shelling-wheels, of part H, provided with projection or projections h , inserted above the bevel runners at their larger diameter, for the purpose of deflecting the corn-ears against the shelling-wheels, substantially as specified. 75

LOUIS GILLET.
